Application February 9, 1929, Serial No. 338,744

53 Claims.

(Cl. 93—5)

Our invention relates to packaging machines of a type especially adapted to handle straws, tooth picks or similar articles, to enclose a predetermined number of them within a tube and thereafter to seal the ends of the tube in a continuous series of operations which take place automatically and under the most improved sanitary conditions.

The embodiment of the invention, which will hereinafter be described, is especially constructed to package so-called "drinking straws" of the type used in connection with soda and soft drink dispensaries, but it will be clear that it will only require a change in the dimensions of certain instrumentalities of the invention to accommodate tooth picks or other articles either smaller or larger than the straws without departing in any way from the spirit of the invention.

According to well known types of straw packaging machines it is the usual practice first to form a tube of paper in a tube forming machine, then to seal one end thereof and thereafter to insert the straws into the preformed tubes, which are then sealed at their other ends. Due to the large number of operations required to successfully carry out the packaging of straws by this means, the machines have been exceedingly complicated in structure and as a consequence extremely expensive to produce and maintain in repair. The main reason for the complications, it is believed, is in the mechanism required preparatory to inserting the straws into the preformed tubes, which must be distorted to receive the ends of the straws and otherwise undergo various manipulations before the contents finally reach a point where the ends of the tube may be sealed.

With the foregoing in mind it is the principal object of our invention to provide a packaging device of the character embodying certain novel instrumentalities adapted to form the container in the shape of a continuous tube, which advances over a predetermined number of the straws held stationary in a rotary conveyor, is severed and further advanced into the conveyor to completely enclose the straws, and thereafter is carried by the conveyor to bring its opposite ends into the path of sealing means adapted to close the tube beyond the ends of the enclosed straws.

We accomplish this object by means of the mechanisms hereinafter fully described, set forth in the appended claims and illustratively exemplified in the accompanying drawings, in which Figure 1 is a perspective view of our improved packaging machine; Figure 2 is another perspec-

tive view of the same viewed from another angle; Figure 3 is a transverse sectional view of the invention showing the hopper for the straws, the rotary conveyor and associated parts; Figure 4 is an end elevational view of the rotary conveyor; Figure 5 is a substantially longitudinal sectional view of one end of the conveyor; Figure 6 is a plan view of the machine; Figure 7 is a plan view of a portion of the rotary conveyor showing the position taken by the straws while being inclosed by a tube; and Figure 8 is a perspective view of the tube cutter and associated parts for operating it and advancing the tube over the straws.

Referring to the drawings in detail, 10 denotes the articles to be packaged, namely the straws, which are deposited in a hopper 11 composed of upright end and front walls 12 and an inclined rear and bottom wall 13. The lower end, as well as the upper end of the hopper 11, is open to enable the straws 10 to be placed therein through the top and discharged at the bottom opening into a rotary conveyor 14 above which the hopper is supported by means of upright standards 15a attached at their upper ends to the end walls 12 and at their lower ends to the surface of a flat bed plate 16.

The rotary conveyor 14 comprises a cylindrical member the periphery of which is corrugated to provide parallel longitudinally disposed grooves or compartments 15 to retain the straws 10 during the movement thereover of the tubular receptacle to be described and the crimping operation to close the ends of such receptacle. As illustrated particularly in Figures 3 and 4, a transverse section of each groove 15 comprises a convex bottom wall and slightly converging side walls which join the peripheral surface of the conveyor. The conveyor 14 is supported on and turns with an intermittently rotating shaft 17, which is journalled in bearings 18 on upright spaced standards 19, and which carries on one end beyond the standard 19 a ratchet wheel 20. The length of the conveyor 14 is shorter than the corresponding length of the hopper 11, at least by the combined widths of fixed gauge plate 21 and adjustable stop plate 22 arranged at each end of the cylinder.

The gauge plates 21 are disposed to limit the number of straws 10 to two for each compartment 15 and each plate comprises a segmentally shaped member having a hub portion 23 loosely mounted on the shaft 17 and an inwardly directed marginal portion and rim 24 having its periphery concentric with the periphery of the conveyor from the end of which it is spaced the dis-

tance of the thickness of the stop plate 22, as clearly illustrated in Figure 5. The periphery of the gauge plate 21 brings the surface slightly above or radially beyond the bottoms of the 5 grooves 15 so that when the straws gravitate thereinto while in the hopper 11, only sufficient room is provided between the peripheries of the gauge plates 21 and that of the conveyor to accommodate two straws, as illustrated in Figure 10 4. Of course it will be understood that corresponding arrangement is contemplated for the use of only one instead of two straws if desired.

In the event the packaging machine is to be run for tests or to bring the tube forming mechanism into proper adjustment without feeding straws to the conveyor, the stop plates 22 are utilized and each thereof comprises a segmental member interposed between the cylinder end and the adjacent gauge plate 21 and capable of radial 20 adjustment so as to bring its peripheral surface or end into coincidence with the periphery of the conveyor to close the end of the grooves and thus support the ends of the straws 10 from dropping into the grooves and being conveyed outside the 25 hopper.

The stop plates 22 are entirely supported on their adjacent gauge plates 21 and the support comprises a pin 25 having a screw 26 on its inner end to project through a radial slot 27 in the 30 stop plate 22 and clamp the latter to the pin. The other end of the pin 25 is slidably arranged in a radial slot 28 of the gauge plate 21 and carries a roller 29, the extreme of the pin beyond the roller being adapted to receive one end of a spring 35 30, the other end projecting in a line with the slot 28 and attached to a pin 31 on the gauge plate adjacent the hub thereof. Between the roller 29 and pin 31 and disposed rearwardly of the radial line of the slot 28 is a pivot pin 32 40 upon which is mounted the end of a lifting lever 33 which is provided with a cam surface operating to lift the roller 29 and stop plate 22 when the lever 33 is raised. Raising the lever 33 far enough will cause the cam to pass under the 45 roller and hold it and the plate projected against the action of the spring 30.

The tubes and their straws 10 are held in the grooves 15 of the conveyor, from the hopper 11 to a point of delivery, by a curved shield 34, 50 which is spaced slightly from the periphery of the conveyor, and which is supported on arms 35 projecting from portions of the standards 19.

Intermittent rotary motion is imparted to the conveyor 14, as previously stated, through the 55 ratchet wheel 20, and such motion is effected by a spring actuated pawl 36 which is pivotally carried at the end of an arm 37 and yieldably held in engagement with the ratchet wheel 20 by means of a spring 38. The arm 37 is pivotally carried at its mid portion on a stud shaft 39 projecting towards the conveyor from a standard 40, the latter being mounted on the bed plate 16. The end of the arm 37 beyond its pivot carries a follower 40a which is yieldably held in contact 65 with a cam 41 by means of a spring 42. The cam 41 is fixed on a continuously rotating power shaft 43 and is provided with one high point thereby causing one forward movement of the conveyor 14 for each rotation of the shaft 43. The power shaft 43 receives its rotary movement through a spur gear 44 carried at its end and in mesh with a pinion gear 45 which is mounted on a shaft 46 having its bearings in a yoke shaped standard 47 and projecting outwardly therefrom to carry a fixed and a loose pulley 48, and a fly wheel 49.

A belt 50 is used to drive the pulleys 48 and a belt shifter 51 controlled by a lever 52 operates on the belt 50 to shift the same from one to the other of the pulleys. A motor not illustrated is employed to carry and drive the belt, the motor being located preferably beneath the bed plate 16. 5

The power shaft 43 projects longitudinally from one end of the machine to the other adjacent the rear edge of the bed plate 16 upon which it is supported in bearings 53. 10

Referring again to the conveyor 14, it has been described that its rotary movement is intermittent, such movement being for the purpose of bringing each groove 15 into a certain position of rest just outside of the hopper 11, in the direction of movement of the conveyor, which movement is clockwise when considered as viewed from the left. This position of rest will be referred to hereinafter as the wrapping station. Therefore at this station there is a common axis which not only coincides with the longitudinal axis but is the axis about which the tubular wrapper is to be formed and along which it is advanced to its wrapping position. As the conveyor 14 pauses in its rotary movement and a pair of straws 10 are supported in stationary position at the wrapping station, they project beyond opposite ends of the conveyor cylinder, but as the wrapper in the form of a tube 54 advances to meet the ends of the two straws and continues to move over and enclose them, there is sufficient frictional engagement between the moving inner surface of the tube 54 and the straws 10 to cause the latter to gradually be carried longitudinally in the direction of movement of the said advancing tube. To arrest this movement of the straws, a stop plate 55 is attached to the side of the hopper 11 and projects across the axis of the wrapping station and consequently in the path of the straws, which no longer being able to move, receive the wrapper 40 which continues to move thereover. The tube 54, in a manner hereinafter described, is severed during its forming operation and advanced to a position enclosing all of the straws except the ends adjacent the stop plate 55. The operation at the 45 wrapping station having been completed, the conveyor is again stepped ahead to bring the next groove into co-alinement with the axis of the wrapping station. The straws enclosed in their wrappers being held in the grooves by the plate 50 or shield 34, reach a point at which they are pushed within the tube, i. e. the straws are returned to a position corresponding to their location before the tube was advanced thereover. The mechanism accomplishing this movement of the 55 straws into the tube 54 comprises a short rod 56 adjustably carried by a block 57, the latter being mounted on an axially reciprocating shaft 58. The rod 56 is aligned with the axis of the tube and consequently when moved toward the latter 60 abuts both straws. The reciprocating movement is imparted to the shaft 58 by means of a horizontally disposed pivoted lever 59, one end of which is attached to the shaft 58, while its pivot 60 is arranged adjacent the other end so that the arcuate movement of the attached end of the lever is along an almost straight line. A small play is provided in the connection between the lever and shaft to take care of whatever deviation from the straight line is described by the 65 end of the lever. The shaft 58 is guided in a bearing 61 forming an integral extension of the standard 19, the bearing 61 being provided with a slot to accommodate a pin projecting from the longer end of the lever 59, through the slot 75

and into the shaft 58. The shorter end of the lever 59, projecting towards the power shaft 43 is provided at its free end with a roller follower 62 which is yieldably held in engagement with the surface of a cam 63 by a spring 64 disposed at its ends between the shorter end of the lever 59 and a fixed post 65 projecting upright from the bed plate 16. The cam 63 is fixed on the power shaft 43 adjacent the cam 41 and comprises a disc rotating in upright position and provided with a short high point 66, which is disposed to engage the roller 62 during a rest period of the conveyor or at a time just subsequent to the interval during which the high point of the cam 41 has completed its effect upon the arm 31, pawl 36 and ratchet wheel 20 to advance the conveyor from one rest position to the next.

Subsequent to the operation of the pusher or rod 56 to center the straws 10 in the tubular wrapper and during the conveying movement of the cylinder 14, the ends of the tube beyond the ends of the straws are subjected to the operation of two sets of so called crimping rollers 67, one roller of each set being mounted on a shaft 68 which is mounted adjacent its opposite ends in suitable bearings 69 in the standards 19. The other roller of each set is rotatably mounted at the upper end of a lever 70 which is pivotally carried at its mid portion on a pin 71 projecting from the inside face of the standard 19. Tension is exerted at the lower end of the lever 70 to urge the crimping roller at the other end yieldably into operative relation with the other roller of the same set. Crimping devices of this character are well known and are now used to seal the ends of the tube wrappers such as those contemplated for use in the present invention. A spring 72 is used to tension the lever 70, one end of the spring being attached to the lower end of the lever while the other end is fixed in a rod 73 projecting from an upstanding plate 74 on the bed plate 16. The other end of the rod projects through and beyond the plate where it is threaded and carries a thumb nut 75, which, adjustable as it is over the rod 73, operates to set the latter at predetermined distances from the lever itself, whereupon the spring tension on the lever is variable.

It is understood that the actual crimping action on the ends of the tubes takes place by rotary motion of the crimping rollers 67 and during traverse of the said ends between the crimping rollers of each set. Rotary motion is imparted to the rollers on the shaft 68 through a gear connection comprising a large spur gear 75 mounted on and turning with the conveyor shaft 17 between the ratchet wheel 20 and standard 19, as illustrated in Figure 1, and a pinion gear 76 in mesh with gear 75 and mounted on the end of the shaft 68. According to this construction the intermittent rotary motion of the conveyor shaft 17 is participated in by the spur gear 75, which being of so much greater diameter than that of the pinion gear 76 causes the latter and crimping wheel shaft 68 to rotate with corresponding speed.

An ejecting attachment is incorporated in the machine to guide the sealed wrappers out of their respective grooves in the conveyor subsequent to the end sealing operation. The lower end of the conveyor shield plate 34 projects to a line just below the line on which the end crimping rollers operate on the tubes, so that as the conveyor carries the wrapped straws downwardly from under the shield the normal tendency of the packages is to drop out of their grooves in the

conveyor. To insure this discharge a pair of arms 77 are mounted on a rocker beam 78 so as to bring their free ends on an elevation above that of the ends of the wrapper when the latter is being conveyed out from under the shield. The 5 rocker beam 78 comprises a shaft mounted in bearings 79 arranged closely to the surface of the bed plate 16 and having radial arms 80 projecting toward the front of the machine. The elevation of the free ends of the ejecting arms 77 10 is timed so as to move into positions at opposite ends of the conveyor above the discharging groove 15, just as the conveyor is about to move a step ahead. The rocking motion is imparted to the beam 78 by means of a cam 81 mounted 15 and turning with the power shaft 43 and located thereon along a portion projecting in the rear of the conveyor, which cam 81 engages a follower roller 82 carried adjacent the mid portion of an arm 83 fixed at one end to the beam 78. 20 The high portion of the cam 81 holds the ejectors in their uppermost positions during the rotary movement of the conveyor so that the wrapped articles will have their ends moved under the free ends of the arms 77 and during continued 25 rotation of the conveyor the wrapped articles will be forced downwardly out of its groove. The arm 83 projects beyond the roller 82 to form a nose to engage the surface of the bed plate and prevent movement of the ejector arms to an elevation too far above the necessary path of effective operation.

It has been found in practice that the straws 10 in the hopper 11 do not always gravitate to the bottom thereof in proper positions to edge 35 their way into the grooves 15 and in order to more or less arrange the straws over the grooves we provide a pair of rotary brushes 84, turning in a direction the same as that taken by the conveyor and brushing the surface thereof as 11- 40 illustratively exemplified in Figure 3. The brushes 84 are arranged adjacent opposite ends of the hopper and are carried by a shaft 85, which has its bearings in the end walls 12 and which projects outside the hopper at one end to carry a 45 pulley 86. A belt 87 drives the pulley 86 from a second pulley 88 keyed to the power shaft 43. The belt 87 is crossed to drive the pulley 86 and brushes 84 in the same direction as the conveyor itself. Shields 89 are attached to the front wall 50 of the hopper 11 in positions to embrace the brushes except at their lower portions.

Referring now to the tube forming mechanism and to the shears for severing the tube and then projecting it over the straws 10, particular reference will be had to Figures 2, 6 and 8. The tubes 55 54, as is well known, are formed by curving a web of narrow paper 90 longitudinally upon itself so that its sides overlappingly engage. The web 90 is drawn from a roll and the shaping is done 60 in a die 91 through which it passes on the way to a crimping roller 92. The roller 92 is continuously driven during operation of the machine through a shaft 93, worm connection 94, and shaft 95 which is driven through a train of gears 65 96 by the power shaft 43. The tubular wrappers, as previously stated, are formed along the axis of the wrapping station and, as shown clearly in Figure 6, a substantial space is provided in the wrapping station between the crimping roller 92 70 or the rear of the wrapper and the ends of the straws being held in the station. In this space a severing device is mounted and operated to first sever the advancing tube and then shove it ahead over the straws at a speed greater than the speed 75

of the following tube being formed by the crimping roller 92.

The mechanism for effecting the severing and pushing operation comprises a pair of shears 97, illustrated in detail in Figure 8. The shears 97 are supported at their pivotal connection on a bracket 98 carried at one upright side of a slide rod 99 which is square in transverse section and mounted to reciprocate longitudinally in a guideway disposed in the upper portion of a standard 100, the latter being arranged to carry the crimping roller shaft bearings 101 of the shafts 93 and 95. The shears 97 comprise the ordinary cutting blades terminating, on the opposite side of their pivot screw 102, in rearwardly projecting extensions 103 and 104, lower extension 103 being straight and forming part of the uppermost blade, while the extension 104 is a part of the lower blade and projects upwardly and rearwardly at an inclination and then straight back to a position directly over the lower extension 103. The normal tendency of the blades is to close and the means used is a spring 105 which is connected at its lower end to the lower extension 103 and at its upper end to a post 106 projecting upright from the end of the upper extension. The tension of the spring 105 is, therefore, exerted to pull the extensions toward each other. The shears 97 are operated along a path taken by the tubes 54 between the crimping roller 92 and the receiving end of the conveying cylinder 14, that is to say, the blades are arranged so that one is above the tube and the other beneath. When the blades are open, the tube being formed merely travels along between them, but when released to closed position under the tension of the spring 105, the blades sever the tube transversely thereof. By a longitudinal movement of the blades more rapid than that of the normal movement of the tube, the severed portion partly enclosing the straws 10 is advanced to its final position in the groove of the conveyor by the closed shears. The means used to release the shears 97 and permit them to remain closed until the tube is pushed home comprises a two armed rocker plate 107 disposed in upright position closely adjacent the vertical plane of the two extensions 103 and 104 of the shears. The plate 107 is mounted at its center on a longitudinal reciprocating rock shaft 108, which is carried at one end by a bearing 109 attached to the free end of the square slide rod 99 and on the upright side thereof opposite that occupied by the first bracket 98. Each of the ends of the plate 107 carries a roller 110, one thereof engaging the extensions 103 and 104 just rearwardly of the pivotal connection and the other roller 110 engaging under the free end of the upper extension 104. The shaft 108 beyond the bearing 109 in the direction opposite that taken by the tube being formed, projects into the bore of an oscillating tubular member 111, which turns in a bearing 112 mounted on the standard 100, and which is provided with a slot 113 disposed longitudinally along its side to accommodate a stop and guide pin 114 fixed to the shaft 108 which slides in the tubular member 111. The length of the slot 113 corresponds with the longitudinal movement of the shaft 108 necessary to push the tube the distance between the point of shearing and the home position in the wrapping station. The pin 114 operates to limit the longitudinal movement of the shaft 108 and to impart the partial rotation thereto from the tubular member 111.

On the end of the tubular member 111 beyond

its bearing 112 an arm 115 is mounted. The arm 115 projects forwardly of the axis of the member 111 and is attached to the upper end of a link 116, the lower end thereof being connected to the end of a lever 117, which projects toward the power shaft 43, and which is pivotally mounted adjacent the rear end on a pivotal mounting 118, also formed as an integral part of the standard 100. The end of the lever 117 beyond the pivot carries a roller 119 which is yieldably held down upon a cam 120 by a spring 121 disposed between the lever on the rear portion beyond the pivot and the bed plate. The cam 120 is keyed to the power shaft 43 and its lower portion allows the follower to drop suddenly, which motion is transmitted through lever 117, link 116 and tubular member 111, finally rocking shaft 108 to release the shears 97 and permit them to close about the advancing tube. The severing operation takes place when the shears 97 have been withdrawn with the slide rod 99 to a position closely adjacent the crimping roller 92.

The slide rod 99 projects through the upper portion of the standard 100 and outwardly at the right side thereof. As illustrated clearly in Figure 2, the projecting end of the rod 99 is forked and provided with curved slots 122 through which a bolt 123 projects. Between the ends of the fork the upper end of an upright lever 124 is mounted on the bolt 123. The lower end of the lever 124 is pivotally mounted on a pin 125 projecting from the rear face of an extension of the lower portion of the standard 100 and at an elevation above the pivot 125 the lever 124 carries on its rear face a roller follower 126, which is disposed in the path of a cam 127, the roller 126 being held in contact with the cam by a spring 127a which tends to urge the shears yieldably towards the conveyor. The cam 127 is mounted on a cam shaft 128 disposed counter to the power shaft 43 and projecting between upright portions of the standard 100. Rotary motion is imparted to the shaft 128 by a pair of miter gears 129 one thereof being mounted on the end of the shaft 128 and the other on the power shaft 43, as illustrated in Figures 2 and 6.

The operation of the machine, which has been described in detail in the foregoing description, is summarized in the following: Assume that the conveyor 14 has been operated a sufficient number of steps to fill its grooves 15 with straws 10, and that the first groove 15 of the conveyor 14 has been brought to rest in the line of the so called wrapping station, and in the present instance contains two straws 10 with their opposite ends projecting beyond the opposite ends of the groove, as illustrated in Figure 7. During the movement of the conveyor 14 and in fact continuously throughout the operation of the machine, the paper web 90 is being folded, crimped by the roller 92 and fed in the direction of the conveyor 14. Perfect alinement of the groove 15 and tube at the wrapping station is essential and further care must be taken to provide the inner diameter of the tube of a dimension very slightly greater than the combined diameters of the two straws 10 so that, as the tube advances, it may envelop the projecting ends of the straws and continue to travel longitudinally thereof until the greater portion of the tube is inside the groove 15. Contact of the wall of the tube with those of the straws being enveloped causes the latter to follow the movement of the oncoming tube for a short distance or until the opposite

75

ends of the straws abut the stop plate 55.

The tubular wrapper having been completed throughout its full length, the shears 97 move, through the operation of the cam 127, to a position adjacent the crimping roller 92 where the blades of the shears close to sever the tube and remain closed while the cam 127 returns the shears to its initial position adjacent the receiving end of the conveyor. The movement of the shears being more rapid than that of the following portion of the oncoming tube the severed wrapper is moved out of the way of the latter and driven home over the straws.

Step by step, the conveyor 14 carries the enclosed straws 10 and wrappers 54 to a point where the pusher rod 56 pushes the projecting ends of the straws back into the center of their wrapper. The next step of the conveyor brings the ends of the wrapper beyond the ends of the straws into the path of the crimping rollers 67, which close and seal the wrapper ends during movement of the conveyor from one position of rest to the next. As a final operation, the ejector arms 71, having been raised to positions above the groove on opposite ends of the conveyor cylinder, are in position above the wrapper and, during the next conveying movement of the conveyor the wrapper is carried from beneath the shield plate 34 and forced downwardly out of its groove 15 by the inclination of the arms 71 with respect to the relative path of movement of the groove.

Having now described our invention and the manner in which the same operates what we claim and desire to secure by Letters Patent is:

1. In a machine for packaging articles, the combination of means for forming a continuous tubular wrapper, means for conveying the articles into position to be enveloped by the oncoming wrapper, means for cutting off the wrapper during movement thereof over the articles, and means for simultaneously closing both ends of the wrapper.

2. In a machine for packaging articles, the combination of means for forming a continuous tubular wrapper, means for conveying the articles into position with their ends protruding to be enveloped by the oncoming wrapper, means for cutting off the wrapper during movement thereof over the articles, means for centering the articles in the wrapper, and means for simultaneously closing both ends of the wrapper.

3. In a machine for packaging articles, the combination of means for forming a continuous tubular wrapper, a hopper to hold the articles, means for conveying the articles from the hopper into position with their ends protruding to be enveloped by the oncoming wrapper, means for cutting off the wrapper during movement thereof over the articles, means for centering the articles inside the wrapper, and means for simultaneously closing both ends of the wrapper.

4. In a machine for packaging articles in tubular receptacles, means for supporting said articles with their ends positioned so that the receptacles may be advanced over said ends, means for advancing the receptacles over said ends of the articles, and means for simultaneously closing both ends of the receptacles.

5. In a machine for packaging articles in tubular receptacles, means for supporting the mid portion of the articles with the ends of the latter projecting so that the receptacles may be advanced over said ends, means for advancing the

receptacles over the projecting ends of the articles, and means for simultaneously closing both ends of the receptacles.

6. In a machine for packaging articles in tubular receptacles, an intermittently rotating conveyor for the articles, means for advancing the receptacles over the ends of the articles and into the conveyor during a stationary position thereof, means for centering the articles in the receptacles during a subsequent stationary position of the conveyor, and means for closing the ends of the receptacle during rotary movement of the conveyor.

7. In a machine for packaging articles in tubular receptacles, an intermittently rotating conveyor, means for feeding the articles to said conveyor in predetermined numbers, means for advancing the receptacle over the ends of the articles and into the conveyor, during a stationary position of the latter, means for centering the articles in the receptacle during a subsequent stationary position of the conveyor, and means for closing the ends of the receptacle during subsequent rotary movement of the conveyor.

8. In a machine for packaging drinking straws, an intermittently rotating conveyor for carrying segregated groups of the straws, means for forming continuous tubular wrapping material and enveloping the ends of the group of straws in its advance movement toward the latter and during a stationary position of the conveyor, means for severing the advancing wrapper and subsequently advancing it a greater axial speed to a position centered in the conveyor and about the straws, means for holding the wrapped straws in the conveyor, means for intermittently rotating the conveyor, means operated during a stationary position of the conveyor beyond the wrapping position to center the straws in the wrapper, and means operated by rotary movement of the conveyor to close simultaneously both ends of the wrapper projecting outside the holding means.

9. In a machine for packaging drinking straws, an intermittently rotating conveyor comprising a cylindrical member having uniformly spaced longitudinally disposed grooves in the peripheral surface, a hopper to supply straws to said grooves, means disposed at the ends of the cylinder to partly close the ends of the grooves and support the ends of a predetermined number of straws in each groove as it passes, means for forming a continuous tubular receptacle and advancing it to envelop the ends of the straws projecting beyond the conveyor during a stationary position thereof, means for cutting off a length of the receptacle and completing its movement over the straws at an increased axial speed, means for centering the straws in the receptacle enclosing the straws in the groove of the conveyor during a subsequent stationary position, means for supporting the wrapped straws in their grooves, to the point of discharge, means for closing the ends of the wrappers during rotary movement of the conveyor, and means operating beyond the holding means to eject the wrappers from the grooves during subsequent rotary movement of the conveyor.

10. In a machine for packaging drinking straws, the combination of means for forming a continuous tubular wrapper, means for severing the wrapper in predetermined lengths during axial movement thereof and thereafter advancing the severed wrapper at an increased axial speed over the straws to be wrapped.

11. In a machine for packaging drinking

- straws, the combination of means for forming a continuous tubular wrapper, shears for severing the wrapper in lengths during axial movement thereof, means for operating the shears, 5 and means for reciprocating the shears axially of the moving wrapper to project the length of wrapper at a speed greater than normal movement of the wrapper from the forming means.
12. In a machine for packaging drinking straws, the combination of a rotary conveyor having longitudinal grooves to carry the straws in groups, a segmental plate at opposite ends of the conveyor to partly close the ends of the grooves to support the ends of the straws to prevent more than a predetermined number from being contained in the grooves, and a plate adjustably carried by each of the first plates to project completely over the ends of the grooves to exclude the straws from said grooves.
13. In a machine for packaging drinking straws, means for forming a tubular receptacle and advancing the same to envelop the projecting ends of the straws held in stationary position, means for completing the movement of the receptacle over the straws at an increased rate of speed, and means for closing the end of the receptacle.
14. In a machine for packaging straws or similar articles, the combination of means for forming a charge of such articles, and means for forming a wrapper for such articles, said wrapper forming means being active to propel the formed wrapper into encompassing relation to the charge.
15. In a machine for packaging straws or similar articles, the combination of means for forming a charge comprising a plurality of such articles, and means for simultaneously forming a wrapper for such articles and for forcing the wrapper, after being formed, into encompassing relation to the charge.
16. In a machine for packaging straws or similar articles, the combination of means for forming a charge of such articles, and means for continuously forming a wrapper for such articles, formed portions of the wrapper, during the continuous formation, being forced over the charge.
17. In a machine for packaging straws or similar articles, the combination of means for forming a charge of such articles, and means for continuously forming a wrapper for such articles and advancing the continuously formed wrapper over, after it has been formed, the charge.
18. In a machine for packaging straws or similar articles, the combination of means for forming a charge of such articles, and means for continuously forming a wrapper for such articles and successively advancing the formed portions of the wrapper over successive charges.
19. In a machine for packaging straws or similar articles, the combination of means for forming a charge of such articles, means for forming a wrapper for such articles, said wrapper forming means being active to propel the wrapper after its formation into encompassing relation to the charge, and means for cutting the formed tubular wrapper to predetermined lengths while effecting the encompassing action.
20. In a machine for packaging straws or similar articles, the combination of means for forming a charge of such articles, means for simultaneously forming a wrapper for such articles and forcing the formed portions of the wrapper into encompassing relation to the charge, and means for cutting the formed tubular wrapper to predetermined lengths while effecting the encompassing action.
21. In a machine for packaging straws or similar articles, the combination of means for forming a charge of such articles, means for forming a wrapper for such articles, formed portions of the wrapper, during the formation thereof, being forced over the charge, and means for severing the formed tubular member into predetermined lengths while being forced over successive 10 charges.
22. The method of wrapping straws or similar articles in tubular containers which includes the steps of: continuously forming and advancing the tubular container, positioning a charge of 15 such articles in the path of the advancing tubular container, and encompassing the charge in the advancing container.
23. The method of filling tubular containers which includes the steps of: continuously forming and advancing the tubular container, positioning charges of articles in the path of the advancing tubular container, encompassing the charges in the advancing container, and severing the advancing container into predetermined 25 lengths.
24. The method of filling tubular containers which includes the steps of: continuously forming and advancing the tubular container, positioning charges of articles in the path of the advancing tubular container, encompassing the charges in the advancing container, and severing the advancing container into predetermined lengths as each charge is encompassed by the advancing container.
25. The method of filling tubular containers which includes the steps of: continuously forming and advancing the tubular container, positioning charges of articles in the path of the advancing tubular container, encompassing the charges in the advancing container, and severing the advancing container into predetermined lengths after each charge has been partly encompassed by the advancing container.
26. The method of filling tubular containers which includes the steps of: continuously forming and advancing the tubular container, positioning a charge of articles in the path of the advancing tubular container, encompassing the charge in the advancing container, and severing 50 a predetermined length of the advancing container.
27. The method of filling tubular containers which includes the steps of: continuously forming and advancing the tubular container, positioning a charge of articles in the path of the advancing tubular container, encompassing the charge in the advancing container, and severing a predetermined length of the advancing container after it has encompassed the charge.
28. The method of filling tubular containers which includes the steps of: advancing the tubular container, positioning a charge of articles in the path of the advancing tubular container, supporting the advancing container, and encompassing the charge in the supported advancing container.
29. The method of filling tubular containers which includes the steps of: continuously forming and advancing the tubular container, positioning a charge of articles in the path of the advancing tubular container, encompassing the charge in the advancing container, and arranging the charge in a predetermined relation within the container.

30. The method of filling tubular containers which includes the steps of: advancing the tubular container, positioning a charge of articles in the path of the advancing tubular container, supporting the advancing container, encompassing the charge in the supported advancing container, and arranging the charge in a predetermined relation within the container.

31. The method of filling tubular containers which includes the steps of: continuously forming and advancing the tubular container, positioning a charge of articles in the path of the advancing tubular container, encompassing the charge in the advancing container, severing the advancing container into predetermined lengths, and arranging the charge in a predetermined relation within the container.

32. The method of filling tubular containers which includes the steps of: continuously forming and advancing the tubular container, successively positioning charges of articles in the path of the advancing tubular container, encompassing the charges in the advancing container, successively severing predetermined lengths of the advancing container as each charge is encompassed by the advancing container, and arranging the charge in a predetermined relation within the container.

33. The method of filling tubular containers which includes the steps of: continuously forming and advancing the tubular container, successively positioning charges of articles in the path of the advancing tubular container, encompassing the charges in the advancing container, successively severing predetermined lengths of the advancing container after each charge is encompassed by the advancing container, and arranging the charge in a predetermined relation within the container.

34. The method of filling tubular containers which includes the steps of: continuously forming and advancing the tubular container, successively positioning charges of articles in the path of the advancing tubular container, encompassing the charges in the advancing container, successively severing predetermined lengths of the advancing container after each charge has been partly encompassed by the advancing container, and arranging the charge in a predetermined relation within the container.

35. The method of filling tubular containers which includes the steps of: continuously forming and advancing the tubular container, successively positioning charges of articles in the path of the advancing tubular container, encompassing the charges in the advancing container, successively severing predetermined lengths of the advancing container after each charge has been partly encompassed by the advancing container, arranging the charge in a predetermined relation within the container, and closing the ends of the container.

36. The method of filling tubular containers which includes the steps of: continuously forming and advancing the tubular container, successively positioning charges of articles in the path of the advancing tubular container, encompassing the charges in the advancing container, successively severing predetermined lengths of the advancing container after each charge has been partly encompassed by the advancing container, arranging the charge in a predetermined relation within the container, and simultaneously closing both ends of the container.

37. The method of filling tubular containers which includes the steps of: continuously forming and advancing the tubular container, positioning a charge of articles in the path of the advancing tubular container, encompassing the charge in the advancing container, severing a predetermined length of the advancing container, and advancing the severed length over the charge at greater speed than that of the continuously advancing container.

38. The method of filling tubular containers which includes the steps of: continuously forming and advancing the tubular container, positioning a charge of articles in the path of the advancing tubular container, encompassing the charge in the advancing container, severing a predetermined length of the advancing container after it has encompassed the charge, and advancing the severed length over the charge at greater speed than that of the continuously advancing container.

39. In a machine for packaging articles in tubular containers including means for supporting and feeding the tubular container in one direction, and supply means for the articles including a feeding device for positioning the articles in the path of movement of the tubular container, the feeding and supply means being constructed so that the articles are retained by the device and automatically become enveloped by the supported container as the latter moves with relation to the device.

40. In a machine for packaging articles in tubular containers including means for supporting and feeding the tubular container in one direction, and supply means for the articles including a feeding device for positioning a charge of a plurality of the articles in the path of movement of the tubular containers, the feeding and supply means being constructed so that the charge is retained by the device and automatically becomes enveloped by the supported container as the latter moves with relation to the device.

41. In a machine for packaging articles in tubular containers including means for supporting and feeding the tubular container in one direction, and supply means for the articles including a feeding device for positioning a charge of a plurality of the articles in the path of movement of the tubular container and transversely of which the container moves, the feeding and supply means being constructed so that the charge is retained by the device and automatically becomes enveloped by the supporting container as the latter moves with relation to the device.

42. In a machine for packaging articles, the combination of means for forming and feeding a tubular wrapper, means for conveying the articles into position with their ends projecting to be enveloped by the oncoming fed wrapper, means for centering the articles in the midportion of the wrapper, and means for closing the ends of the wrapper.

43. In a machine for packaging articles, the combination of means including a former for forming and feeding a tubular wrapper open at both ends, a hopper to hold the articles, means for conveying the articles from the hopper into the path of the fed wrapper with their ends protruding to be enveloped by the oncoming wrapper, and means for closing both of the wrapper ends.

44. In a machine for packaging articles, the

- combination of means for forming and feeding a tubular wrapper, a hopper to hold the articles, means for intermittently conveying the articles from the hopper into the path of the fed 5 wrapper with their ends protruding to be enveloped by the oncoming wrapper, means for centering the articles in the mid-portion of the wrapper, and means for closing the wrapper ends.
- 10 45. In a machine for packaging articles, the combination of means for forming and feeding a tubular wrapper, means for conveying the articles into the path of the oncoming wrapper, to be enveloped by and within the wrapper after 15 it has been formed, means for closing the wrapper ends, and means for ejecting the wrapped articles from the conveying means.
- 20 46. In a machine for packaging articles, the combination of means for forming and feeding a tubular wrapper, a hopper to hold the articles, means for conveying the articles into the path of the oncoming wrapper, to be enveloped by and within the wrapper after it has 25 been formed, means for limiting the number of articles for each wrapper, and means for simultaneously closing both ends of the wrapper.
- 30 47. A machine for packaging articles comprising a support, means for feeding an article to said support, means including a former for forming a blank into a container open at its opposite ends, means for feeding the open ended container over the article on the support, and means for completely closing said opposite ends 35 of the container.
- 35 48. A machine for packaging articles comprising means including a former for forming a container open at both ends, means for positioning an article at a predetermined position, means for moving said container from said 40 former and partially over said article, additional means for moving said container to a position in which said article is further enclosed within the boundaries of said container, and means for closing both ends of said container.
- 45 49. A machine for packaging articles, comprising means including a former for forming a container, means for positioning an article at a predetermined position, means for moving said 50 container from said former and partially over said article, additional means for moving said container to a position in which said article is further enclosed within the boundaries of said container, and means for closing both ends of said container.
- 5 50. A machine for packaging articles comprising means including a former for forming a wrapper into an open-ended container, means for moving said container part of the way from said former and over the article to be wrapped, additional means adapted to engage the rear end of said container and move said container further over said article, and means for closing both ends of said container. 15
- 20 51. A machine for packaging articles comprising means including a former for forming a container, means for positioning an article adjacent said former, means for moving said container over said article, said last mentioned means comprising a member adapted to engage the rear end of said container and move said container toward said article, and means for closing both ends of said container. 25
- 30 52. A machine for packaging articles comprising a carrier for carrying a plurality of articles along a predetermined path, means including a former for forming containers open at opposite ends, means for moving said containers over said articles when said articles arrive at a given position in the path along which said articles move, and means for thereafter completely closing both ends of said containers. 35
- 40 53. In a packaging machine, the combination with means for forming tubular members open at their opposite ends out of wrapping material, of means for supporting and moving a plurality of articles along a defined path, means for moving said tubular members over said articles without moving said articles out of their general path of movement, and means for completely closing said open ends of the tubular members. 45

ALBERT M. GOLDSTEIN. 50
MAYER GARFINKEL.
